(57) **CLAIM**

The ornamental design for a footwear foxing tape, as shown and described.

DESCRIPTION

FIG. 1 is a front perspective view of a footwear foxing tape showing my new design;

FIG. 2 is a lateral side elevational view thereof;

FIG. 3 is a medial side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken lines in FIGS. 1–7 represent portions of the footwear that form no part of the claimed design.
